UNITED STATES PATENT OFFICE

92,839

DESIGN FOR A CONDIMENT CONTAINER

Ray Fara, La Porte, Ind., assignor to La Porte Specialties, Inc., La Porte, Ind., a corporation of Indiana

Application May 3, 1934, Serial No. 51,676

Term of patent 3½ years

To all whom it may concern:

Be it known that I, RAY FARA, a citizen of the United States, residing at La Porte, in the county of La Porte, State of Indiana, have invented a new, original, and ornamental Design for a Condiment Container, of which the following is a specification, reference being had to the accompanying drawing forming a part thereof.

I claim:

The ornamental design for a condiment container as shown.
